SCARF

Frank P. Cianciolo, 138 Whitfield St.,
Guilford, Conn. 06437

Filed Aug. 14, 1972, Ser. No. 280,147

Term of patent 7 years

Int. Cl. D2—03

U.S. Cl. D2—358

FIG. 2.

FIG. 3.

FIG. 4.

FIG. 1 is a perspective view of my scarf when spread out on a plane surface;

FIG. 2 is an end view taken from the left of FIG. 1;

FIG. 3 is a top plan view of a scarf;

FIG. 4 is a side elevational view thereof; and

FIG. 5 is a perspective view thereof in wearing position, the showing of a wearer being for purposes of illustration.

I claim:

The ornamental design for a scarf, as shown and described.
